UNITED STATES PATENT OFFICE.

FREDERIC LEON HERBIN, OF LYNN, MASSACHUSETTS, ASSIGNOR OF ONE-HALF TO THOMAS J. GALLIVAN, OF LYNN, MASSACHUSETTS.

FOLDING RACK.

No. 908,000.

Specification of Letters Patent. Patented Dec. 29, 1908.

Application filed September 25, 1908. Serial No. 454,771.

To all whom it may concern:

Be it known that I, FREDERIC LEON HERBIN, of Lynn, in the county of Essex and State of Massachusetts, have invented 5 certain new and useful Improvements in Folding Racks, of which the following is a specification.

This invention relates to racks, such as are used for supporting boots and shoes in 10 factories during different stages of the process of manufacture, although my invention hereinafter described may be embodied in racks for other purposes, such as supporting garments and other articles 15 while they are being dried.

The invention has for its object to provide a rack having a plurality of shelves or rack members adapted to be folded into compact compass so that a number of racks 20 may be stored in a relatively small space when not in use, and to be readily extended and the members thereof securely supported in their operative position.

The invention consists in the improvements which I will now proceed to describe 25 and claim.

Of the accompanying drawings, forming a part of this specification,—Figure 1 represents a perspective view of a rack embodying my invention, the rack being shown in 30 its operative position. Fig. 2 represents an end elevation of the same, the rack being folded. Fig. 3 represents a transverse section through a portion of the rack.

35 The same reference characters indicate the same parts in all figures.

In the drawings, 12, 12 represent a pair of vertical supporting standards which rise from supporting feet 13.

40 16, 16 represent a series of frame rods rigidly inserted at their ends in sockets formed for their reception in the standards 12, said rods extending across the space between the standards and rigidly connecting the latter, the standards, feet and frame rods constituting a rigid frame. The frame rods also serve as supports for the rack members hereinafter described, and as partitions between the supporting portions 45 of the rack members. Each of the said rack members includes two end bars 17, 17 mounted to oscillate upon one of the frame rods 16, and two series of rack rods 18 inserted at their ends in sockets formed for 50 their reception in the end bars 17, one

series being arranged at one side, and the other at the opposite side of the fixed frame rod 16.

19, 19 represent continuous legs which are jointed to the ends of the cross bars 60 17 at one side of the supporting standards, and are extended below the cross bars of the lower rack member far enough to bear upon the supporting feet 13 when the rack members are horizontally arranged in their 65 operative position, as shown in Fig. 1.

20, 20 represent the upper members of sectional legs, said members being jointed to the ends of the cross bars 17 opposite the ends to which the legs 19 are jointed. 70 21, 21 represent the lower members of the said sectional legs, said lower members being jointed to the lower ends of the upper members 20 and to the cross bars 17 of the lower rack member, and adapted to extend 75 downwardly and bear upon the feet 13, as shown in Fig. 1, the said feet being preferably provided with spring catches adapted to engage holes in the lower ends of the leg members 21.

80 It will be seen that when the rack is adjusted in its operative position, shown in Fig. 1, the rack members are rigidly supported at both sides of the standards 12 by the continuous legs 19, and the sectional legs composed of the members 20 and 21. When it is desired to fold the rack, as shown in Fig. 2, the lower ends of the leg members 21 are disengaged from the feet 13 and swung upwardly beside the upper members 20, thus 90 leaving the ends of the rack members at one side of the standard 12 unsupported. These unsupported ends are therefore free to swing downwardly, the opposite ends and the legs 19 being correspondingly raised until the 95 legs 19 come to a bearing on one side of the standards 12, and the leg members 20 and 21 come to a bearing on the opposite side of said standards, the rack members being inclined and bearing against each other, so that 100 they occupy a space of considerably less width than when they are horizontally arranged.

105 It will be seen that a number of racks folded, as in Fig. 2, may be packed in a relatively close compass, the feet 13 of the several racks being adapted to overlap each other because the space between the feet is unobstructed, the necessary rigid connections between the standards 12 being pro- 110

vided by the fixed frame rods 16 which are located above the feet. The frame rods 16 are located above the inner rack rods 18 so that they constitute stops or partitions at the 5 central portions of the rack members adapted to prevent shoes deposited on one series of rack rods 18 from projecting over onto the other series. Each rack, therefore, has two supporting portions which are separated by 10 a frame rod 16. The inner rack rods 18 are lower than the outer rack rods so that each supporting portion is transversely inclined and is highest at its outer edge. Each horizontal frame rod 16 rigidly attached to the 15 vertical standards 12 and constituting a part of the rigid frame, serves also two other functions; that is to say, it not only constitutes a support on which a rack member composed of two cross bars 17 and the rack members 20 18 attached thereto is adapted to oscillate, but it also constitutes an adjunct of the said rack member, by reason of the fact that it supports the inner ends of the articles deposited on the rack rods 18, as indicated in 25 Fig. 3.

I claim:

1. A folding rack comprising a rigid frame composed of a pair of vertical standards, rigidly attached supporting feet projecting 30 from opposite sides of the standards and separated from each other by an unobstructed space, and a vertical series of horizontal frame rods rigidly attached at their ends to said standards and extending across 35 the space between the latter, rack members composed of cross bars mounted in pairs on said frame rods and free to oscillate thereon, and rack rods attached to said cross bars and extending parallel with the frame rods, each 40 frame rod constituting not only a frame member, but also a support on which a rack member is adapted to oscillate, and an adjunct of the said rack member, the series of 45 rack members being adapted to be inclined to reduce the rack to compact form, and means for rigidly supporting said members in their operative position.

2. A folding rack comprising a pair of vertical standards rigidly attached, having supporting feet projecting from opposite sides 50

of the standards and separated from each other by an unobstructed space, a vertical series of frame rods rigidly attached at their ends to said standards and extending across the space between the latter, cross bars 55 mounted in pairs on said connecting bars and free to oscillate thereon, and horizontal rack rods attached to said cross bars and extending parallel with the frame rods, each pair of cross bars and the two series of rack rods 60 connected therewith constituting a rack member, adapted to be inclined to reduce the rack to compact form, each frame rod constituting not only a frame member, but also a support on which a rack member is adapted 65 to oscillate, and an adjunct of the said rack member, contiguous legs jointed to the ends of the cross bars at one side of the supporting standards, and adapted to bear on the standard feet, and sectional legs jointed to the 70 ends of the cross bars at the opposite side of the standards and also adapted to bear on the standard feet, the lower members of the sectional legs being displaceable to permit the swinging of the members to their inclined 75 position.

3. A folding rack comprising a pair of vertical standards, a vertical series of frame rods rigidly attached at their ends to said standards and extending across the space between 80 the latter, said standards and rods being members of a rigid supporting frame, and rack members composed of cross bars mounted in pairs on said frame rods and free to oscillate thereon, and rack rods attached to 85 the cross bars and extending parallel with the frame rods, the rack rods of each rack member being arranged in two series at opposite sides of the supporting frame rod, the latter being higher than the inner rack rods 90 and constituting a support on which the rack member is adapted to oscillate and a stop to limit the inward movement of articles deposited on the rack rods.

In testimony whereof I have affixed my 95 signature, in presence of two witnesses.

FRED. LEON HERBIN.
